[57] **CLAIM**

The ornamental design for an aeroponic plant grower with plant support, as shown and described.

DESCRIPTION

FIG. 1 is a front perspective view of an aeroponic plant grower with plant support showing my design;

FIG. 2 is a front elevational view thereof;

FIG. 3 is a top plan view thereof;

FIG. 4 is a bottom plan view thereof;

FIG. 5 is a right side elevation view thereof;

FIG. 6 is a rear elevation view thereof; and,

FIG. 7 is a left side elevation view thereof.

The broken line showing of a utility cord in FIG. 1 of the drawing is for illustrative purposes only and forms no part of the claimed design.
